Attorneys

UNITED STATES PATENT OFFICE.

GEORGE CANELL, OF CINCINNATI, OHIO.

TRUSS STRUCTURE.

Application filed October 8, 1924. Serial No. 742,330.

An object of my invention is to provide a truss structure wherein the pad holder is removably mounted.

Another object is to provide a device of this kind which may be adapted to either left or right side hernial application.

Another object is to provide a truss which is convertible by a dealer or user to either left side or right side adaptation.

Another object is to provide a device of this kind which is capable of adjustment as to the pressure of the pad upon the body of the wearer.

These and other objects are attained by the means described herein and disclosed in the accompanying drawings, in which:

Fig. 1 is a perspective view of a truss of my invention, parts being broken away.

Fig. 2 is a cross sectional view on line 2—2 of Fig. 1.

Fig. 3 is a cross sectional view taken on line 3—3 of Fig. 1.

The truss of my invention comprises a body band 5 which may be a flat spring steel band adapted to pass partially about the waist of the wearer. A suitable covering means which may comprise strips of leather 6 and 7 are secured together along their longitudinal edges and are adapted to extend beyond the end 8 of the spring 5 to provide a belt 9. The forward end of the spring 5 is provided with a pair of spaced threaded perforations 10 and the forward layer 7 of the belt 9 is provided with registering perforations 11.

The reversible pad holding structure comprises a bar 12 having its opposite ends developed into flattened plates 14. Within each of the plates 14 is disposed a pair of perforations 13 adapted to register with the perforations 10 and 11 in the spring 5 and belt 9 respectively, and a threaded perforations 15 adapted to receive the threaded end of a button stud 16. Intermediate the plates 14 on the bar 12 is disposed an enlarged shouldered block 17 provided on its one side with serrations or teeth 18. On either side of the shouldered block 17 the bar 12 is developed into a substantially rounded portion 19 about which the curved arms 20 of the pad holder plate 21 are adapted to be turned so that the pad holder

plate is mounted for rotation about the plate 12 between the ends 14 thereof. The plate 21 is suitably recessed at 22 for receiving the shouldered block 17 between the curved arms 20. A spring pawl 23 is secured at its one end to the plate 21 by any suitable means such as rivet 24 and is adapted to have its other end 25 in engagement with the teeth 18 on the shouldered block 17. A suitable pad structure 26 is mounted upon the plate 21 on the side opposite the spring pawl 23 and the entire plate and ratchet mechanism is encased in the suitable cover 65 member 27 which may be of leather or any other suitable material. A suitable protective cap 28 is adapted to be passed over one of the ends 14 of the bar 12 and to be held thereon by means of the button stud 16. 70 The remaining plate portion 14 of the bar 12 is then inserted between the end of the spring 5 and the side 7 of the belt 9 whereupon suitable screws 29 are passed through the perforations 11 and 13 in the side 7 and plate 14 respectively and engage in the threaded perforations 10 in the spring 5 whereby the pad holder structure is securely mounted upon the end of the spring 5.

The truss of my invention as shown in Fig. 1 is adapted for exerting pressure upon the right hand side of the body of a wearer. The belt and spring portion are passed about the right side of the waist of the wearer and secured in position by passing 85 the button stud 16 through one of the perforations 30 in the belt 9 whereupon the pad 26 will extend downwardly and exert pressure against the body of the wearer. If the pressure is insufficient, the plate 21 is pressed 90 toward the body of the wearer whereupon the said plate will revolve slightly about the rounded portions 20 of the bar 12 until the end 25 of the spring pawl 23 passes over one of the ratchet teeth 18 on the shouldered block 17. The end 25 of the spring pawl 23 engaging the side of one of the teeth 18 precludes the return of the pad holder and in this manner adjusted pressures may be attained.

It will be noted that there has been provided a truss structure which does not require special parts for the opposite sides of the body and which may be carried in stock

by a dealer or manufacturer and fitted to the needs of the individual customer with a minimum of effort.

What I claim is:

5 In a device of the class described the combination of a spring belt adapted to pass about one side of the waist of a wearer, a flexible sheath for the spring belt elongated to completely encircle the waist of a wearer,
10 a pad holder bar provided with uniform end

portions each adapted at different times to be secured to one end of the spring belt, an adjustable pad holder on the bar, and means for securing the free end of the flexible sheath to one of the end portions of the pad 15 holder bar.

In testimony whereof, I have hereunto subscribed my name this 16th day of September, 1924.

GEORGE CANELL.
